[57] CLAIM

The ornamental design for a light duty target mechanism, as shown and described.

DESCRIPTION

FIG. 1 is a perspective view of the light duty target mechanism;

FIG. 2 is a right side elevational view of the light duty target mechanism;

FIG. 3 is a left side elevational view of the light duty target mechanism;

FIG. 4 is a plan view of the light duty target mechanism;

FIG. 5 is a front elevational view of the light duty target mechanism;

FIG. 6 is a rear elevational view of the light duty target mechanism; and

FIG. 7 is a bottom view of the light duty target mechanism.

The target board shown in broken lines in FIG. 1 has been disclosed for illustrative purposes only.
